UNITED STATES PATENT OFFICE.

PAUL MEDIATE, OF EAST YOUNGSTOWN, OHIO.

AIRSHIP-PROPELLING MECHANISM.

Application filed October 26, 1925. Serial No. 64,988.

The object of this invention is the provision of a propelling mechanism for air craft that is provided with lifting propellers and with other propellers designed to be influenced by the currents of air and which operate other propellers in the nature of wind wheels which create a forced draft through tubes forming part of the construction and which propel the craft.

10 To the attainment of the above broadly stated object and others which will appear as the nature of the invention is better understood, the improvement resides in certain novel features of construction, combination and operative association of parts, a satisfactory embodiment of which is illustrated by the accompanying drawings.

In the drawings:—

Figure 1 is a side elevation of the improvement with parts broken away.

20 Figure 2 is a top plan view thereof.

Figure 3 is a front elevation thereof.

In the showing of the drawings, I make use of a series of superimposed longitudinally extending tubes. Four tubes 1 constitute the upper series and an equal number of tubes 2 constitute the lower series, while three tubes 3 comprise the intermediate series. Each series of tubes are surrounded and supported by ring members 4 which have web connections 5 between each other. The intermediate series of tubes 3 are of a less length than the upper and lower series of tubes 1 and 2, and the portions of the tubes 1 and 2 projecting beyond the intermediate tubes 3 have their ends widened at the upper portions thereof, as indicated by the numeral 6. The widened portions are in the nature of housings and have journaled transversely therethrough shafts 7. Fixed on each of the shafts in each of the housings 6 there is a fan propeller 8. The outer ends of the tubes 1 and 2 proper, at their juncture with the housings 6, have downwardly extending flanges 8' and these flanges are in the nature of baffle elements for directing the currents of air onto the lower blades of the fan propellers 8.

40 In the end tubes 3 of the intermediate series there are fixed supports 9 for motors 10 that have on their outwardly extending shafts 11 traction propellers 12. The passage through the central intermediate tube is uninterrupted and the motors 10 may be

controlled by mechanism actuated from cars 55 13 which are suspended by means 14 from the outer tubes 2 of the lower series.

The cars 13, in the present instance, are in the nature of water craft, so that the device may be considered in the nature of 60 a hydro-aeroplane.

65 On the sides of the outer tubes 1 and 2, there are fixedly secured open frames 15 and supported on each of these frames there is a curved longitudinally extending sustaining plane 16. Of course the planes are suitably braced to the frames and to the tubes. In each of the open frames 15 there is a rudder 17, controlled by flexible means 18 leading into the cars 13.

70 By reference to Figure 3 of the drawings it will be noted that the shafts 7 for the fan wheels or tractor propellers 8 are arranged in pairs, one pair passing through bearing openings in each of the outer pair of upper 75 and lower tubes 1 and 2, and centrally secured on each of these shafts 7, between the adjacent housings 6, there is a gear wheel 19 that meshes with a pinion 20 on a longitudinally extending shaft 21. Each shaft 21 80 is, of course, journaled in suitable bearings and the forward end of the shaft, which projects beyond the front of the device, has secured thereon a screw 22.

85 The traction propellers 12 are put in operation for the initial ascent of the craft. The craft is sustained in the air by the sustaining planes. The propellers 12 are also in operation when the craft is in the air, but, after the craft has attained a desired speed 90 the screws 22 will be influenced by the air currents and the turning of these screws will revolve the projecting propellers 8. The propellers 8 create a forced suction of draft through the tubes 1 and 2 which will project 95 the craft through the air, and after the craft has attained a desired speed the motors 10 may be shut off to permit of the idling of the propellers 12.

100 The improvement is, of course, susceptible to such changes and modifications as fall within the scope of the appended claims.

Having described the invention, I claim:—

1. An airship propelling mechanism comprising superimposed series of tubes, motor 105 driven traction propellers supported by the intermediate tubes, wind influenced screws at the front of the upper and lower series of

tubes and projecting propellers in the rear of the said upper and lower series of tubes operated by the last mentioned screws.

2. An airship propelling mechanism, comprising superimposed series of longitudinally directed horizontally disposed tubes, the inner series of tubes being one less in number than the upper and lower series, means connecting all of the tubes, motor driven propellers projecting beyond the front of the end intermediate tubes, air influenced screws at the front of the tubes of the upper and lower series, projecting propellers in the last mentioned tubes operated by the turning of the screws and sustaining planes extending beyond the sides of the tubes.
3. An airship propelling mechanism, comprising series of longitudinally extending

horizontally disposed series of tubes, the intermediate series being one less in number than the remaining series and being of a less length than the remaining series, motor driven propellers extending forwardly from the outer intermediate tubes, said last mentioned series of tubes having their outer ends formed with housings and having baffle plates depending from the inner faces of the housings, projecting propellers revoluble in each of the housings, air actuated screws at the front of the upper and lower series of tubes, operable for imparting motion to the projecting propellers, sustaining planes extending beyond the sides of the upper series of tubes, and rudders supported below and to the rear of the sustaining planes.

In testimony whereof I affix my signature.
PAUL MEDIATE.
